HOSIERY DISPLAY DEVICE

Robert Kayton, Jackson Heights, Walter Freundel, Brooklyn, Harry R. Jeter, New York, and Beatrice Dudek, Garden City, N. Y., assignors to Chadbourn Sales Corporation, a corporation of New York

Application October 8, 1953, Serial No. 384,872

4 Claims. (Cl. 206—78)

This invention relates to display devices, and in particular to a device of this sort for displaying hosiery and the like.

The device of the present invention is adapted especially for displaying ladies' hosiery for examination so that a merchandising stock does not need to be disturbed while a selection of the particular type of hosiery desired is being made by a customer. Briefly described, this hosiery display device is characterized by an upstanding display board having display envelopes arranged thereon to contain reeled hose with a portion of the hose extended therefrom for display in relation to color identification means or other indicia which may be carried by the display envelope.

These and other features of the hosiery display device of the present invention are described in detail below in connection with the accompanying drawing, in which:

Fig. 1 is a perspective view of a hosiery display device embodying the present invention;

Fig. 2 is a top plan view of the hosiery display device shown in Fig. 1;

Fig. 3 is a vertical section taken substantially on the line 3—3 in Fig. 2;

Fig. 4 is a plan view of an unfolded display envelope such as is shown incorporated in the hosiery display device illustrated in Figs. 1, 2 and 3.

Fig. 5 is a plan view opposite to that in Fig. 4 and showing the reel panel of the display envelope folded in place with a hose reeled thereon while leaving a hose portion extended for display;

Fig. 6 is a plan view corresponding to Fig. 5 with the cover panel of the display envelope shown folded in place and interlocked with the folded reel panel; and

Fig. 7 is a perspective view of a display envelope having a reeled hose contained therein and ready for mounting on the display board.

Referring now in detail to the drawing, the upstanding display board referred to above is incorporated in the embodiment illustrated in two portions as indicated by the reference numerals 10 and 12, these display board portions 10 and 12 being joined in angled relation and assembled uprightly with a base plate 14 to form a standing structure.

Each display board portion 10 and 12 is fitted with upper and lower support rails as at 16 and 18, and 20 and 22, that are mounted horizontally in spaced relation and have the respective opposed faces thereof grooved as at 16', 18' and 20' and 22', for engaging and supporting the previously mentioned display envelopes which are indicated generally by the reference numeral 24 and from which the hose are extended for display as at H.

The form of these display envelopes 24 is shown in detail in Figs. 4 to 7 of the drawings. Fig. 5 shows a plan of the unfolded display envelope 24 in which its developed form is seen to comprise a main or front face panel 26 having foldably joined thereto at one side edge a reel panel 28; at the other side edge a back cover panel 30; at the top edge a top mounting edge portion 32; and

2

at the bottom edge a spacer portion 34, to which in turn is foldably joined at its remote edge a bottom mounting edge portion 36.

The reel panel 28 serves to carry the reeled hose H with in the display envelope 24, and Fig. 5 shows the reel panel 28 folded behind the front face panel 26 for this purpose. The reel panel 28 has its top and bottom edges notched as at 38 and 40 to receive the reeled hose H thereon in general alignment with a notch or aperture 42 in the front face panel 26 and through which aperture 42 the hose portion to be displayed may be extended from the reel panel 28.

The back cover panel 30 is provided to retain the reeled hose H in place once it has been arranged on the reel panel 28, and for this purpose the cover panel 30 is formed at its remote side edge with tab portions as at 44 and 46 proportioned for insertion through the reel notches 38 and 40 to interlock with the reel panel 28 in generally covering relation with respect to a hose H reeled thereon as illustrated in Fig. 6.

Fig. 7 shows the display envelope 24 fully folded and interlocked with a reeled hose H contained therein and extended for display, and with the spacer portion 34 folded to arrange the bottom mounting edge portion 36 in relation to the top mounting edge portion 32 ready for insertion in the grooves 16' and 18' (or 20' and 22') of the support rails 16 and 18 (or 20 and 22). It will be noted that the front face notch 42 through which the hose H is extended for display may be advantageously arranged adjacent the bottom of the front face panel 26 so that a major portion of the front face panel 26 remains available to carry indicia such as identifying legends as at 48 or complementary dress fabric samples as at 36.

The mounted disposition of the display envelopes 24 is such that the front face panels 26 are inclined outwardly in a downward direction with respect to the display board portions 10 and 12, so that the extended portions of the hose H hang freely from the display envelopes 24 onto the base plate 14 for easy handling and examination, as seen in Figs. 1, 2 and 3. This arrangement is provided by a spacing of the support rails 16 and 18 (or 20 and 22) at an extent less than the length of the display envelope front face panel 26, so that the spacer portion 34 must be folded to an angled relation with respect to the front face panel 26 in order to engage the mounting edge portions 32 and 36 in the support rail grooves 16' and 18' (or 20' and 22'). This arrangement also results in biasing the mounting edge portions 32 and 34 within these support rail grooves by reason of the folding bias of the spacer portion 34 with the front face panel 26.

The hosiery display device of the present invention may also be fitted with a suitable illuminating means as at 52 mounted adjacent the top edges of the display board portions 10 and 12, and may have other decorative devices arranged thereon as desired, such as a mirror piece 54 arranged behind a model figure 56.

The present invention has been described in detail above for purposes of illustration only and is not intended to be limited by this description or otherwise except as defined in the appended claims.

We claim:

1. A display device for hosiery and the like, said device comprising an upstanding display board and a base plate assembled therewith and forming a standing structure, means on said display board forming opposed mounting grooves disposed horizontally in spaced relation, and at least one display envelope formed of flexible material and having a notched front face through which a portion of hosiery contained therein may be extended for display in relation to said display board, said envelope further

having top and bottom angularly bent edge portions fitted within said mounting grooves and retained thereby.

2. A display device for hosiery and the like, said device comprising an upright board and a base plate assembled therewith and forming a standing structure, means on said upright board forming opposed mounting grooves disposed horizontally in spaced relation, and at least one display envelope formed of paperboard and having a notched front face through which a portion of hosiery contained therein may be extended onto said base plate for display, said envelope front face further having a top edge portion foldably joined thereto and disposed within one of said mounting grooves and a foldably joined bottom edge portion disposed within the other of said mounting grooves, the bottom edge portion being foldably joined to an interposed spacer portion that is foldably joined in turn to said envelope front face.

3. A display device as defined in claim 2 and further characterized in that said envelope front face has a reel panel foldably joined at one side edge for disposition in

4
back thereof, and a cover panel foldably joined at the other side edge and formed with tab portions for interlocking in covering relation with said reel panel.

5
4. A display device as defined in claim 2 and further characterized in that the length of said envelope front face exceeds the spacing between said mounting grooves.
